UNITED STATES PATENT OFFICE.

ANTON E. NIELSEN AND LANGDON GEER, OF NEW YORK, N. Y.; SAID NIELSEN
ASSIGNOR TO SAID GEER.

CLOTH-STAMPING MACHINE.

1,108,929.

Specification of Letters Patent. Patented Sept. 1, 1914.

Application filed February 23, 1909. Serial No. 479,598.

To all whom it may concern:

Be it known that we, ANTON E. NIELSEN and LANGDON GEER, citizens of the United States, residing at New York city, New York, have invented certain new and useful Improvements in Cloth-Stamping Machines, of which the following is a clear, full, and exact description.

This invention relates to an arrangement for stamping cloth.

It is oftentimes very desirable for those who handle, treat or manufacture cloth to stamp a mark indicating quality or proprietorship at frequent intervals throughout its length, and the object of this invention is to provide an efficient, economical and convenient arrangement for carrying out this object. For the purposes of illustration we have shown our arrangement as forming a part of a machine which performs no other function than that of stamping and folding the cloth as it passes therethrough, but it is obvious that our arrangement may be also used as an attachment to other machines such as cloth winding machines and the like.

Our invention will be defined more particularly in the appended claims.

In the embodiment shown in the drawings, Figure 1 is a side elevation of the entire machine; Fig. 2 is a front elevation of that part of the machine which supports the stamping devices taken through section line 2—2 Fig. 1; Fig. 3 is a sectional view through line 3—3 Fig. 2; Fig. 4 is a detached view of one of the stamping members partly shown in section; and Fig. 5 is a face view of one of the stamps.

The main frame of the machine is indicated in general by 1 and may consist of any convenient arrangement of upright and horizontal beams such as shown. The cloth to be stamped is indicated by C, and as shown in Fig. 1 passes from the rear of the machine, through a tension device 3 and 4, over a guide pulley 60, under the stamping roller 2, over a guide pulley 5, and thence to the forward part of the machine between driving rollers 6 and 7, down through the guide 9 to the table 10, upon which it is folded by the device hereinafter described. At the rear portion of the machine are two uprights 1^a, and between these uprights is located the stamping mechanism which acts to stamp any desir-

able figure or character upon the cloth at equal intervals. In Fig. 2 I have shown the cloth as stamped by such a character, in the present case the letter "A" surrounded by a circle. Between the uprights 1^a and located one at each side of the machine are two upright guide frames 26 having a horizontal portion 26^a, and adjustably mounted in these guide frames are sliding bearing blocks 28. These blocks are supported in position by the devices shown more particularly in Fig. 3, in which a hanger 29 threaded to engage the horizontal cross portion 26^a of the upright 26 extends downward and has a loose connection with the bearing block 28. This loose connection as shown consists of an enlarged portion upon the lower end of the screw-spindle which is received in a recess in the bearing block so that the movement of the impression cylinder toward the stamping devices is limited by the engagement of the upper wall or top of the said recess with the said enlarged portion. This hanger may be operated by its hand wheel to lift or lower the bearing and block in its guide frame as may be desired. A spring 31 is shown between the bearing block and the underside of the cross piece 26^a to maintain the bearing block normally in its lower position, but allowing it to yield upwardly. Mounted in the bearing blocks 28 is the cloth roll 2, and directly below this cloth roll and mounted in fixed bearings in the main frame is the stamp-carrying shaft 11. Upon this shaft are mounted several stamping devices indicated generically by 33. Fig. 4 shows the specific construction of one of the stamping devices, and as there shown, consists of a collar for surrounding the shaft 11 and adapted to be fixed thereto by stud 33^a. Extending in opposite directions from said collar are tubular sleeves 34; having a slit 34^a, and inserted in this sleeve is the stem 35 of the stamp, the face of which is indicated by 39. A collar 36 surrounds the slotted sleeve 34, and by means of a stud screw 36^a passing through this collar the slotted sleeve 34 may be made to tightly grip the stem of the stamp. The upper portion of this stem 35 is shown as threaded and having in engagement therewith an adjusting nut 37, which is for the purpose of adjusting the stamp in and out of the sleeve 34. The stem 35 and the 110

5 sleeve 34 are preferably keyed to each other to prevent the stamp from turning therein. As shown in Fig. 2 the stamps are mounted on the shaft 11 at spaced intervals across the width of the cloth.

10 Referring to Fig. 2 it will be seen that directly below the stamp-carrying shaft are a series of upright rods 40 and slidably mounted on said rods are a series of bearing blocks 41, and mounted in said bearing blocks are a series of inking rolls 42, preferably three in number, and having their peripheries in contact. In fact these inking rolls rest upon each other by their peripheries. Below the 15 lowest inking roll is shown attached to the main frame an ink fountain 43. In order to adjust the inking rolls toward and away from the stamping devices, we have provided set screws 45 contacting and supporting the lowermost bearing block 41, and pairs of set screws 46 and 47 resting against the upper side of the uppermost bearing blocks 41 at each side of the machine. By loosening the set screws 46 and 47 and screwing up set screws 45, it will be plainly understood that the entire series of bearing blocks with their inking rolls will be simultaneously adjusted upwardly.

20 In all arrangements for stamping cloth it has been found to be of the utmost importance that an accurate adjustment between the stamp and the cloth is necessary and also between the stamp and its inking roll. Otherwise if the stamp were too close to the 25 cloth roll, it would in its rotation smear and injure the cloth, and if it were too close to the inking roll it would be injured by contact therewith. In the present embodiment we have shown as above described the cloth 30 roll adjustable toward and away from the stamping devices, and in addition as mounted in bearings which may yield in an upward direction away from the stamping devices, so that by no possibility can the 35 stamps press against the cloth with too 40 much force.

45 Any convenient arrangement may be employed to drive the various operating parts of this mechanism, but in the preferred construction which we have shown, a power shaft 12 driven by pulley 13 and belt 14 is mounted on the main frame and is connected to drive the stamp-carrying shaft 11 by means of meshing gears 15 and 16. It is 50 necessary of course that the cloth roll as well as the inking rolls be driven at the same peripheral speed as the stamping devices, and therefore should be positively connected therewith by some suitable gearing. We 55 have shown gears 48, 49 and 50 mounted on the outer end of each one of the inking roll shafts and meshing with each other so that the inking rolls rotate together at all times. The gear 49 of the middle inking roll is 60 driven from the stamp-carrying shaft 11 by 65

means of a chain 51, and an idler 52 is adjustably mounted on the main frame to bear against this driven chain 51 in order to take up the required slack in the chain when the rolls are adjusted. The cloth roll is driven from the stamp-carrying shaft by means of meshing gears 15 and 17 shown at the right-hand side of Fig. 2. The shaft 11 also drives the drive roll 6 at the forward part of the machine by means of a gear 18 and connecting chain 19. The roll 7 is driven by peripheral contact with the roll 6 and cooperating with roll 6 acts to pull the cloth through the machine. A folding frame is mounted at the front of the machine and consists of a rocking arm 8 pivoted to the shaft 22 and having guides 9 at its lower end. The arm 8 is driven by the sprocket wheel 23 by means of connecting pitman 25 and the sprocket wheel 23 receives its rotation from shaft 22 by means of a connecting chain 24.

70 The tension device shown at the rear end of the machine consists of two separated and horizontal rods 34 between which the cloth passes, mounted to rock about the shaft 3 by means of a worm wheel fixed thereto, said worm wheel being operated by a hand wheel 4 having a worm engagement therewith.

75 It will thus be seen that we have provided a convenient arrangement for passing cloth through the machine under any desirable tension with means to stamp a character on said cloth at equal intervals, and means to finally fold the cloth in a pile after it has 80 passed through the machine.

85 What we claim is:

1. An arrangement for stamping cloth comprising in combination a main frame, a cloth roll mounted in bearings thereon, a rotating stamp carrying shaft having one or more tubular sockets fixed thereto and a stamping device having a stem adjustably secured in each of said sockets, said shaft having a gearing connection with said cloth roll, means for transferring ink to said stamping devices comprising a series of three inking rolls peripherally in contact, all mounted in line, said lowermost roll adapted to supply ink and said uppermost roll adapted to contact with the said stamping devices for transferring ink thereto, and a positive gearing connection from said stamping shaft to said middle inking roller, and means for adjusting said stamp carrying shaft and said cloth roll toward and away from each other.

2. An arrangement for stamping cloth comprising in combination a main frame, a cloth roll carried in bearings on said main frame and adapted to yield upwardly, a stamp carrying shaft mounted below said cloth roll and provided with one or more stamping devices arranged in pairs and oppositely disposed for acting against said cloth.

cloth roll from beneath the same, a series of inking rolls for said stamping devices mounted in adjustable bearings below said stamping shaft and diametrically opposite said cloth roll, and power devices and gearing connections for driving said stamping devices and said inking rolls at the same peripheral speed as said cloth roll.

3. An arrangement for stamping cloth comprising in combination a main frame, having upright guide frames at each side thereof, bearing blocks adjustably mounted in said guide frames and adapted to yield upwardly, a cloth roll carried in said bearing blocks, a stamp carrying shaft mounted in bearings directly below said cloth roll and provided with one or more stamps adjustably fixed thereto, vertical guide rods on said main frame below said shaft, and a series of separate bearing blocks slidably mounted on said guide rods, one above the other, each block having an inking roll mounted therein, an ink fountain mounted adjacent said lowermost inking roll, and means for adjusting said inking rolls simultaneously toward and away from said stamp carrying shaft, a power shaft connected to drive said stamp carrying shaft, and gearing connections to said inking rolls and said cloth roll.

4. In a cloth stamping machine in combination, a main frame having a series of cloth rolls mounted thereon and power devices for driving said rolls to pass cloth over the same from the rear to the front of the machine, one of said cloth rolls being adjustably mounted in said main frame and adapted to yield upwardly, stamping devices rotatably mounted directly beneath said yielding cloth roll, a series of contacting inking rolls mounted in separate bearings adjacent said stamping devices and si-

multaneously adjustable with relation thereto, a hand operated tension device at the rear of said main frame for creating a tension on said cloth as it passes to said stamping devices.

5. An arrangement for stamping cloth comprising in combination a main frame, a cloth roll adjustably mounted in upwardly yielding bearings, a rotary stamp-carrying shaft mounted beneath said cloth roll having oppositely disposed stamping devices carried thereon, and ink-transferring means comprising a series of three inking rollers for said stamping devices mounted below the same and adjustable relative thereto, said cloth-roll stamp-carrying shaft and inking rollers being all mounted in line.

6. An apparatus for stamping cloth comprising in combination a main frame, a cloth roll mounted thereon, a rotatable stamp-carrying-shaft, stamping devices thereon, means for adjusting said stamp-carrying-shaft and said cloth-roll toward and away from each other, and means for transferring ink to said stamping devices comprising a series of three inking rolls peripherally in contact, the lowermost roll of said series supplying ink and said uppermost roll contacting with said stamping devices for transferring ink thereto, and a positive gearing connection from the middle inking roll of said series, whereby the said lowermost and uppermost rolls are driven from said middle roll.

Signed at New York, N. Y., this 17th day of February 1909.
